PHILIP D. PARSONS, OF PHILADELPHIA, PENNSYLVANIA, ASSIGNOR TO SCOTT PAPER COMPANY, A CORPORATION OF PENNSYLVANIA.

PAPER TOWEL FOR TOILET PURPOSES.

1,158,549.

Specification of Letters Patent.

Patented Nov. 2, 1915.

Application filed March 27, 1915. Serial No. 17,410.

To all whom it may concern:

Be it known that I, PHILIP D. PARSONS, a citizen of the United States, and resident of Philadelphia, county of Philadelphia, and 5 State of Pennsylvania, have invented an Improvement in Paper Towels for Toilet Purposes, of which the following is a specification.

This invention relates to paper towels for 10 toilet-purposes and has for an object to provide a package of folded paper towels which shall be compact and suitable for use within a serving cabinet in such manner that individual towels may be successively withdrawn as desired.

More particularly, the object is to provide 15 a package of paper towels each of which is so folded and arranged as to provide positive and effective folded parts or means to be engaged by a discharging blade operatively mounted upon the cabinet whereby exterior manipulation of the said blade causes either the said folded parts or means to be readily engaged and pushed through the discharge 20 opening of the cabinet where it may be grasped and the towel withdrawn without objectionably disturbing the remainder of the towels within the cabinet.

More specifically stated, the folded towel 25 sheets may be considered as having a body part formed by folding the sheet on two parallel lines upon itself and with the folded ends again folded back upon themselves, and thereby intermediately providing a plurality of parallel folds in the sheet, each of 30 which forms a tab of multi-ply thickness, whereby the said sheet may be suitably positioned within the serving cabinet and present a multi-ply tab for engagement with 35 the discharging blade.

With the above and other objects in view, the nature of which will be more fully understood from the description hereinafter, the invention consists in the novel construction 40 of paper towels as hereinafter more fully described and defined in the claims.

Referring to the drawings: Figure 1 represents a sectional elevation of a portion of the serving cabinet showing the adaptation 45 of my improved paper towel thereto; Fig. 2 represents a side elevation of sheets folded in accordance with my invention and arranged in package form; and Fig. 3 represents a perspective of a portion of one of 50 the towel sheets.

1 designates a preferred type of cabinet for use with the towels of my invention and has its lower part provided with a transverse slot 2 through which the towel tab or means to be engaged by the discharging 60 blade 3 may be projected. The blade 3 may be of any desired form but as here shown it is pivoted and arranged to be reciprocated by the lever 4. The cabinet may also have the shelf or shoulder 5 at the side opposite 65 the blade for supporting the package of towels at one side and, if desired, the opposite or blade side of the cabinet may be similarly provided with a support 6.

Referring more particularly to the folded 70 sheet shown in Fig. 2, 7 designates the body part of the sheet which is formed by folding the sheet in the middle to provide a two-ply body structure which is subsequently folded in the special form now to be described. It is manifest that whether the 75 sheet is single ply or multi-ply is a matter of secondary consideration, though this is the preferred form since it enables a large sheet to be employed having one outer edge 80 as a fold without any exposed single sheet edges, while the two free edges are at the same side of the sheet and abut the wall of the cabinet and are thus protected. Considering the sheet without regard to whether 85 it is single or multi-ply, it is first folded on parallel lines 8 and 9 suitably spaced apart, thereby forming two tab parts extending toward each other in juxtaposed relation, each of which is folded again as indicated at 90 10 and 11 along lines parallel to the respective folds 8 and 9, to provide a suitable width of paper 14 beneath the body of the sheet, and whereby the two ends 12 and 13 of the sheet point in opposite directions and extend or project beyond the folds 8 and 9.

This construction provides two multi-ply tabs provided by part 14 and portions of the tabs 12 and 13, which respectively terminate at equal distances from the free ends 100 of the sheet or the side walls of the cabinet, so that either, according to the position of the sheet within the cabinet, lies in the path of movement of the discharging blade 3. By this construction the built up package 105 of folded sheets is preferably reversible in a horizontal plane within the cabinet without affecting the operative relation between the discharging blade and the multi-ply tab to be engaged.

Sheets folded in the above manner will stack with stability to form a package as the center of gravity will pass through the body part 7 of the sheet between the tab portions. It will also be observed that the sheet is folded to provide multi-ply tab portions 14 pointing in relatively opposite directions and also the tab portions 12 and 13 likewise pointing in relatively opposite directions, so that there is a symmetrical disposition to the paper portions which balances up the package as shown in Fig. 2. I have referred to the reversibility of the package in use in the cabinet, but while this is preferable, I do not restrict myself thereto.

It will now be apparent that I have provided a folded sheet having tabs of multiple thickness parallel to the body portion, which tabs have a free end formed by the folded part of the sheet whereby a relatively strong edge is provided for the discharging blade to engage and push or move the tab toward the discharge slot and through which it is forced so that it assumes a position where it may be grasped in order to withdraw the entire sheet. This construction, furthermore, eliminates, under all conditions, free single edges of the sheet adjacent to the discharging blade, thus avoiding crumpling or displacement of the sheet in the act of discharging.

Having now described my invention, what I claim as new and desire to protect by Letters Patent is:

1. A paper towel consisting of a sheet folded upon itself to form a multi-ply body part, said body part being folded upon two

parallel lines to form tab parts below the body part and extending toward each other, 40 said tab parts being reversely folded along parallel lines whereby two juxtaposed oppositely directed tabs of multiple thickness are provided, and in which the reverse parts of the respective tabs project laterally beyond 45 the body part of the sheet in opposite directions.

2. A paper towel consisting of a sheet having a body part folded upon two parallel lines to form tab parts parallel to the body 50 part and extending in opposite directions, said tab parts being reversely folded along parallel lines whereby two oppositely directed tabs of multiple thickness are provided, one portion of each of which tabs extends 55 laterally beyond the body part of the sheet and oppositely with respect to the corresponding other part.

3. A paper towel consisting of a sheet folded upon two parallel lines to form a 60 middle body part of restricted width, the portions at opposite sides of the body part being again folded upon lines parallel to the first mentioned folds and respectively at a distance therefrom less than the width of 65 the body part to form two multi-ply oppositely directed tabs, and the ends of the sheet constituting parts of said tabs being extended beyond the body.

In testimony of which invention, I here- 70 unto set my hand.

PHILIP D. PARSONS.
